United States Patent

Des. 239,562
Patented Apr. 13, 1976

239,562

ROTARY ACTUATOR

Stephen Matousek and Ulrich H. Koch, Moraga, Calif.,
assignors to Whitey Research Tool Co., Emeryville,
Calif.

Filed May 19, 1975, Ser. No. 578,408

Term of patent 14 years

Int. Cl. D15—99

U.S. Cl. D55—1 G

FIG. 1

FIG. 2

FIG. 3

FIG. 4

FIG. 5

FIG. 1 is a side elevational view of a rotary actuator showing our new design;

FIG. 2 is an end view thereof taken from the right side of FIG. 1;

FIG. 3 is an end view thereof taken from the left side of FIG. 1;

FIG. 4 is a top plan view thereof, the bottom plan view being a mirror image of this top plan view; and

FIG. 5 is a view thereof taken along lines 5-5 of FIG. 4.

We claim:

The ornamental design for a rotary actuator, as shown.
